UNITED STATES PATENT OFFICE.

JOSEPH THIBADEAU, OF SAN FRANCISCO, CALIFORNIA.

MOLD.

1,091,901.

Specification of Letters Patent. Patented Mar. 31, 1914.

Application filed July 23, 1913. Serial No. 780,784.

To all whom it may concern:

Be it known that I, JOSEPH THIBADEAU, citizen of the United States, residing at San Francisco, in the county of San Francisco and State of California, have invented certain new and useful Improvements in Molds, of which the following is a specification.

This invention relates to improvements in molds and more particularly to a device 10 of this character particularly adapted for use in constructing or finishing cornice molding.

The primary object of the invention contemplates the provision of means in the nature 15 of a specially devised mold support or frame, between the brackets or uprights of which a mold board or block is clamped at an angle to the cornice acted upon, this arrangement of the board with respect to the 20 cornice permitting the latter to be entirely made by simply sliding or running the said device thereover.

A further object of the invention contemplates the provision of means including a 25 substantially triangular frame or support upon which the mold block is diagonally clamped, thereby permitting the cornice acted upon to be molded or shaped, the removal of the device being unnecessary at 30 corners for the reason that the miters or corners are completely and properly made from one and the same operation as the cornice itself, thereby avoiding the necessity of using independent tools or devices 35 as heretofore.

The invention still further resides in the provision of a simple and efficient cornice mold wherein the several embodiments comprising the same are so arranged as to permit 40 mold boards of various size and shape to be detachably clamped thereupon.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a detail perspective view illustrating the application of the invention;

Fig. 2 is a top plan view of the device; Fig. 3 is a front elevation; and Fig. 4 is a side elevation of the device.

Before proceeding with the description of the drawings, I desire to call particular attention to the fact that while I have evolved my invention with particular reference to its application in connection with the molding of cornices, the same may be readily utilized for panel or other similar work.

Referring now to the drawings, wherein is illustrated the preferred form of my invention the numeral 1 designates a substantially triangular frame or support upon which the device comprising my invention is arranged, the said support, when in use, being slid or forced along the eaves or base of the cornice acted upon for molding or shaping the cornice itself. A pair of substantially L-shaped brackets 2 are arranged in spaced relation upon the frame 1 near the forward edge thereof, the upright portions of the brackets being braced or supported in rigid relation to each other through the medium of brace rods 3 depending at an angle from the top thereof to the said frame 1, the rods being secured as at 4 at both the top and bottom. Like brackets 5 are arranged upon the support 1 in alinement with the 75 brackets 2 above mentioned, the upright portions of the said brackets 5 being braced by means of brace bars 6 extending from the top to the bottom thereof, the said bars being secured as at 7 to the top and bottom 80 respectively of the brackets.

A mold board or block 8 of any suitable design is adapted to be placed between the upright portions of the brackets 2 and 5 so as to extend at an angle thereto or diagonally thereupon for a purpose to be herein-after fully described. Thumb screws 9 and 10 are carried respectively of the brackets 2 and 5 for the purpose of clamping the said board 8 therebetween, the provision of the 95 said screws 9 and 10 permitting boards of various thickness or size to be employed in connection with the frame or support provided therefor when desired. Handles 11, composed of any suitable material, are disposed so as to embrace the brace rods 3 of the frame, the provision of the handles permitting the entire device to be slid or forced over the cornice acted upon during the application or operation of the invention.

Having described fully the detail construction of the device, it now remains to set

forth a little more in detail the operation thereof.

During the molding of cement cornice work, it has heretofore been necessary to shape or construct the miters or corners of the cornice by hand, which is not only expensive but necessitates the employment of a person skilled in the art. By the provision of a molding device constructed as above described, this objectionable feature is obviated and the miters are properly shaped or constructed with one and the same operation as a cornice itself. After fastening the mold board between the brackets 2 and 5 provided therefor the entire device is placed upon the eaves or base of the cornice and the frame slid or forced throughout the length thereof, the mold board 8 being disposed at an angle to the said frame or support permitting the latter to not only shape and mold the cornice properly but effectually and properly mold the miters thereof, the position of the mold board with respect to the frame being clearly shown in Figs. 1 and 2 of the drawings. The device is first forced along one edge or portion of the cornice until the edge of the mold board 8 fits into the corner or miter of the cornice acted upon, whereupon the continued sliding of the device in the opposite direction will cause the cornice itself as well as the miters to be shaped or molded into proper form.

It will be seen from the above, taken in connection with the accompanying drawings that the manipulation of the thumb screws 9 and 10 will permit mold boards of various size to be readily clamped between the brackets provided therefor; that by disposing the mold board diagonally upon the frame 1, the corners of the cornice can be molded or shaped by forcing the board thereinto; and that by arranging the handles 11 upon the brace rods 3, the former are positioned with respect to the device in the manner desired.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various

minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In a cornice mold, a supporting frame, standards fixedly secured to said frame, said standards being arranged in pairs, the standards of each pair being disposed in widely spaced relation to provide for the arrangement of mold boards varying in thickness therebetween, and means adjustable upon said standards to clamp said mold boards in rigid relation to said standards, as and for the purpose set forth. 65

2. In a cornice mold, an angular supporting frame, standards fixedly secured to said frame, said standards being arranged in pairs, the standards of each pair being disposed in widely spaced relation to provide for the arrangement of mold boards varying in thickness therebetween, and means including a plurality of thumb screws adjustable upon one of the standards of each pair, said screws being adapted for engagement with the mold board acted upon to clamp the same against the other of the standards and in rigid relation thereto, as and for the purpose set forth. 80

3. In a cornice mold, an angular supporting frame, a plurality of substantially L-shaped brackets fixedly secured to said frame, the said brackets being arranged in pairs, the brackets of each pair being disposed in widely spaced relation to provide for the arrangement of the mold boards varying in thickness therebetween, handle-carrying brace rods for the said standards, 90 and means including a plurality of thumb screws adjustable upon one standard of each pair, the said thumb screws being adapted for engagement with the mold board acted upon to clamp the said mold board against the other of the said standards, as and for the purpose set forth. 95

In testimony whereof I affix my signature in presence of two witnesses.

JOSEPH THIBADEAU.
